UNITED STATES PATENT OFFICE

HORACE B. KLEINSMITH, FRANK RODGERS NEEDY, AND FRED W. DOLL, OF ALLEN-TOWN, PENNSYLVANIA, ASSIGNORS TO A. H. BALLIET CORPORATION, OF ALLEN-TOWN, PENNSYLVANIA, A CORPORATION OF PENNSYLVANIA

BOX-WRAPPING MACHINE

Application filed May 31, 1927. Serial No. 195,535.

Our invention relates to mechanism for wrapping cigar boxes.

A purpose of our invention is to provide mechanism adapted to a more efficient, more 5 easy and less expensive application of wraps to cigar boxes than has hitherto been possible.

A further purpose is to register the bottom of a cigar box with a design upon the 10 outside of a glued box wrap while the wrap is on a belt conveyor to a wrapping machine and above a light beneath the conveyor. In order to avoid having the belt become gradually opaque to the light by reason of gradually accumulating glue from the glue machine we preferably isolate the section of 15 conveyor above the light from the portion of the conveyor that receives the wrap from the glue machine.

20 A further purpose is to roll a glued wrap fastener to the bottom of a cigar box part way up one side of the box preparatory to placing the box upon the form of a wrapping machine for side wrapping and preferably 25 while the wrap is still upon a belt conveyor to the wrapping machine.

A further purpose is to slit the turned-up 30 ends of the long side portions of a wrap along the inside of the droplid ends by means of knives rigidly fastened to corner-lap plate 35 holders, preferably slitting upwardly and simultaneously from the four corners before corner-lapping and before turning in the portions of the wrap projecting above the drop-lid ends.

A further purpose is to mount mechanism 40 for slitting a wrap adjacent the droplid ends of a cigar box and mechanism for turning in the portion of a wrap in front of the drop-lid end upon a corner-lap plate support.

A further purpose is to use a corner-lap 45 plate and a cooperating spring to obtain sharp creases between the turned-in portions of the long sides above the droplid ends and the corner-laps thereof said creases extending upwardly and inwardly from the outer corners of the droplid ends.

A further purpose is to spring-press the 50 tops of the side of a wrap along the top edges of the ends during corner-lapping.

A further purpose is to mount a side turn-in member upon spring hinges adapting it to yield upwardly and spring-pressing it downwardly during the turn-in operation at the long sides.

55 A further purpose is to mount spring plungers at the ends of a side turn-in member, using the plungers to maintain the turned-up wrap pressed against the upwardly projecting droplid ends during the operation of 60 cooperating end turn-in rolls over the droplid ends.

A further purpose is to make a roll turn-in over the ends of a cigar box, preferably 65 spring-pressing the roll downwardly upon individual hinges during turn in so as to adapt the roll to easy accommodation to variation in box form.

A further purpose is to roll down the turn-in laps upon the inside of a box preferably 70 making the rear roll operate to substantially the ends of the box, the end rolls operate from the front of the box to the rear roll and the front roll operate from one end roll to the other.

75 We spring-press the rolls outwardly so that they are pushed inward and resiliently press outward while they roll the turn-in laps down inside the box.

A further purpose is to expand the end 80 portions of the turned down turn-in laps, that are above the sides of the box, outwardly against the ends of the box after the rolls have rolled downward, thus pressing the portions of the turn-in lap that cannot be 85 reached by the rolls outwardly against the inside of the box. We support the outward pressure by external presser blocks in order to avoid danger of rupturing the box.

Further purposes will appear in the specification and in the claims.

While our invention is well adapted to use with wrapping machines of widely variant type, we have elected to show it embodied upon a Stokes & Smith type of machine in 95 that it is well adapted to this machine and makes unnecessary detailed description of many parts that are in themselves not part of our present invention. The embodiment shown is convenient and efficient in oper- 100

ation and illustrates particularly well the principles involved.

Figures 1 and 2 are fragmentary top plan and front elevation views of conveyor mechanism embodying some portions of our invention.

Figure 3 is a broken perspective view of structure shown in Figures 1 and 2 and additional linkage for operating a roll shown also in the earlier figures and used for automatically applying the wraps part way upon the backs of the boxes while still on the conveyer of the wrapping machine.

Figure 4 is a fragmentary side view illustrating the support of the roll shown in Figures 1 to 3.

Figure 5 is a broken front elevation of a wrapping machine embodying our invention and showing a portion of the conveyer mechanism of Figures 1 and 2, the last section however of the conveyer being removed to disclose mechanism of the wrapping machine.

Figures 6 to 9 show the upper half of a split form that embodies important features of our invention, the views being respectively top plan, bottom plan and end and front elevations.

Figures 10, 11, 12 and 13 show a modification of the structure illustrated in Figures 6 to 9 and are respectively top plan, bottom plan section on line 12—12 of Figure 10 and front elevation of the modification.

Figure 14 is a perspective view of the bottom half of a split form used in cooperation with the structure shown in Figures 6 to 9 and with very slight modification with the structure shown in Figures 10 to 13.

Figures 15 and 16 are perspective views of slitting mechanism and mechanism for simultaneously corner-lapping and for effecting turn-in at the sides over the droplid ends. The figures illustrate important features of our invention.

Figure 17 is a broken detail showing a box upon its form and operating mechanism, the position being that immediately following corner-lapping, the front roll, front brush and front corner-lap mechanism being removed to show the box.

Figure 18 is a fragmentary longitudinal vertical section through the box, and operating mechanism, during turn-in, the box having moved down to its second position of rest leaving the upper form raised above the box.

Figure 19 is a fragmentary longitudinal elevation of the structure of Figure 18 but taken after the upper form has moved down to lap down the inwardly projecting turn-in laps of the wrap into the box, the position being that of expanding the turned down laps against the droplid ends above the sides.

Figure 20 is a perspective view of one of the side turn-ins.

Figure 21 is a fragmentary end view illustrating the box passing between the front and rear brushes and rolls, while sweeping the wrap up the front and rear sides of the box.

Figure 22 is fragmentary end elevation, part in section, showing a box and slitting, corner-lap, and droplid turn-in mechanism, the position of the parts being the same as in Figure 17.

Figure 23 is an end section of mechanism shown in Figure 18, the position of parts being the same as in Figure 18.

Figure 24 is an end sectional view corresponding to Figure 23, except that the upper form has moved down and is entering the box to lap down the turn-in laps of the wrap into the box.

Figure 25 is an end view in part section of Figure 19 showing the parts in the same position, which is that of pressing the four ends of the end turn-in laps against the inside of the droplid ends.

Figure 26 is a vertical section upon the line 26—26 of Figure 20 showing one of the side turn-ins.

Figure 27 is a perspective view of one of the end turn-ins.

Figure 28 is a vertical section taken upon the line 28—28 of Figure 27, but showing some structure omitted in Figure 27.

Figure 29 is a fragmentary perspective view of structure shown in Figure 19 illustrating mechanism applying the turned down turn-in laps to the droplid ends at and above the long sides.

Figures 30 to 35 are broken perspective views illustrating successive phases of the wrap with respect to the box.

Figure 36 shows a top plan view of a convenient form of wrap before it has been applied to a box.

Figure 37 is a diagrammatic chart illustrating the preferred cycle of operations.

Figure 38 to 55 are small scale views (partly diagrammatic) showing the box and principal operating parts at the principal positions of the cycle.

Figures 38, 39 and 40 show the preliminary roller pasting the back of a wrap part way up the rear side of the box before the box has been removed from the conveyer to be placed by hand upon the form of the wrapping machine, the views being respectively perspective and end and front elevations.

Figures 41, 42 and 43 are corresponding views showing the front and back rollers applying the long sides of the wrap to the box, the views being respectively perspective, sectional end elevation and rear elevation.

Figures 44, 45 and 46 show the mechanism for slitting the side wraps at the droplid ends, lapping the ends and turning in the front and rear sides over the droplid ends, the views being respectively perspective and end and front elevations.

Figures 47, 48 and 49 show the operation of the lower rollers and brushes, the views being respectively perspective and end and front elevations.

5 Figures 50, 51 and 52 show the operation of the side and end turn-ins, the views being respectively a perspective view and front and end sectional elevations.

10 Figures 53, 54 and 55 are corresponding perspective, sectional end elevation and front elevation views and show the operation of the expanding mechanism and pressure blocks for applying the turn-in laps to the inside of the droplid ends at the sides.

15 Like numerals refer to like parts in all figures.

Describing in illustration and not in limitation and referring to the drawings:—

General layout

20 The general layout is shown in Figures 1 to 3 and 5. Figures 1 to 3 show conveying mechanism which is normally operated by the mechanism feeding wraps to a glue machine, not shown, but that is preferably in turn controlled by or synchronized to the operation of the wrapping machine (Figure 5). The feed cylinder of a glue machine, for example, is suitably connected to make one 25 rotation for each reciprocation of the box form on the wrapping machine, each of these latter reciprocations completing the wrapping cycle for one box.

30 Neither the glue machine nor its feed mechanism nor the operating control thereof from the wrapping machine is shown, not being in themselves part of the present invention which is directed to novel operations and mechanisms to be embodied partly in a conveyer and partly in a wrapping machine at the delivery end of the conveyer. The illustrations of the conveyer and wrapping machine with which we show our invention embodied are intended as a conventional illustration for any conveyer and any wrapping machine to which our invention is adapted to be applied.

The conveyer and the registry and the rolling stations thereof

35 The belt conveyer 70 receives the wraps 71 from a suitable glue machine not shown and moves forward with intermittent steps that are of the same length and of a length that 40 is predetermined and usually adjustable.

45 Each time that the box wrapping machine 72 completes its wrapping cycle a new wrap is delivered glue side up from the glue machine to the belt conveyer and the conveyer 50 makes one of its forward movements advancing the wraps already on the conveyer toward the wrapping machine.

55 The successive wraps are thus spaced glue side up along the conveyer at uniform intervals between the glue and wrapping machines

and come to rest successively at the same definite positions or stations between the two machines.

We register the bottom of the boxes to the glued surfaces of the successive wraps at one of these stations and at a later station roll the rearwardly projecting portions of the wraps part way up the backs of the boxes. For this purpose the belt must be relatively offset and desirably narrow.

70 At the registry station we support a transparent plate 73, preferably glass, beneath the belt of the conveyer and place a strong light 74 beneath the plate, the plate and light being both carried upon a frame structure 75, that 75 is in turn carried by and preferably adjustable along side rails 76 of the conveyor.

75 The upper surface of the glass is even with the upper surface of the frame, the two surfaces presenting a firm horizontal support to the bottom of the belt conveyer so that the belt may present firm even support to the successive wraps during the application of the boxes and the frame and glass should be high enough to insure a section of flat belt over the 80 whole surface of the glass.

85 The wraps preferably carry a heavy printed line 77 for registry around the bottom edges of the boxes and as they successively come to rest glue side up over the glass, the lines 77 90 are made visible by the light and used by an operator who places the boxes so that the outer edges of the bottom register with the lines 77.

95 It is old to register a box upon a glued wrap while the wrap is lying upon a glass plate with a light beneath the plate. Hitherto however this has been done after the wrap has been removed from its belt conveyer and we avoid a removal from the conveyer by passing the conveyer over the glass making the light 100 sufficiently strong to shine through the material of the conveyer and making the conveyer of material that will permit this. We have found that a strong light will satisfactorily shine through a conveyer of canvas 105 or like material if the conveyer is reasonably free from glue, but that such material usually becomes gradually opaque to the light if it becomes coated with glue.

110 The conveyer shown comprises three sections connected to operate as a unit, connected by sprockets 78 and chains 79. The first section 80 receives the successive wraps from a glue machine not shown. In practice we have found that the belt 80 becomes gradually 115 coated with glue by reason of glue dropping from wrap stripping mechanism at the glue machine and that this glue coating makes the conveyer become gradually opaque. It can be cleaned at intervals by wire brushes so as 120 to be fully operative for registration over the light but we have found it more desirable to register upon a belt 81 which is free from glue.

125 This is accomplished by making the conveyer in sections, the belts of adjoining sec- 130

tions passing over horizontal parallel rolls 83 and 83' that keep the adjoining belts 80 and 81 from touching yet are sufficiently close to avoid danger of any of the wraps failing to pass from section to section.

5 The second belt 81 receives the wraps from the first and brings them successively to rest over the light and registry plate 73 where an operator places the boxes upon the glued surfaces of the successive wraps in registry with the illuminated bottom edge lines 77.

10 Succeeding forward movements of the conveyers bring the box and wrap to rest on the third belt 81' (the narrowest belt) at a roll 84 for rolling the rearwardly extending portion 85 of the wrap part way up the bottom of the box.

15 The light can be placed under the main belt, but with some sacrifices in clearness as indicated.

20 In order to support the wrap between belts we show a tape 82 which runs with the series of belts i. e. over all of them.

25 In the position upon belt 81' the box and wrap are supported from material bodily movement under the rolling action by supporting members 86 and 86' respectively above and in front of the box at the rolling station. The purpose of this preliminary rolling is to prevent 30 the back of the wrap from hanging down and possibly catching upon the top of the block of the wrapping machine, when the operator places the box upon the form for wrapping as explained later.

35 The roll 84 is carried by a combined guide and bearing 87 having bearing brackets 87' extending upwardly from a horizontal supporting member 87'. The latter member is adapted to slide up and down on the horizontally spaced vertical rods 88 each time a box and wrap are brought to position in front of the roll 84.

40 The bearing brackets 87' are pivoted at 89 to opposite ends of the supporting member 87' and are spring-pressed at 90 toward the box, to an extent limited by screw stops 91 on the member 87. These stops are used for setting the initial alinement of the roll. Until the box comes to rest the roll is lower than 45 the bottom line of the wrap and box.

50 The guide rods 88 depend from a bracket 92 rigidly fastened to the side of the wrapping machine 72 and desirably extended laterally to support the adjacent end of the intermediate section of the conveyer.

55 The supporting member 87 is preferably linked to reciprocate under the action of a rocking member 93 of the wrapping machine, that simultaneously effects the rear corner lapping of a box in the wrapping machine.

60 In Figure 3 the rocking lever 93 of the wrapping machine reciprocates a rearwardly extending link 94 to reciprocate the corner-lap mechanism, and at the same time reciprocates the rearwardly extending link 95, rocker

member 96, forwardly extending link 97 and bell crank 98 to reciprocate the roll supporting member 87.

65 The rocker members 93, 96 and 98 turn respectively in fixed bearings 99, 100 and 101, 70 fastened to the wrapping machine.

The operating connection from the roll 84 to the rocker shaft operating the rear corner laps is particularly advantageous in that it places the operating linkage entirely out of 75 the way of an operator in front of the wrapping machine and at the same time obtains proper synchronism between the reciprocations of the roll 84 and the wrapping machine. The shaft portion of the rocker 93 is rocked by a T member 102 pivoted at 103 and having an operating connection with a cam groove 104 around a drum 105 of the wrapping machine (Figure 5).

80 It will be noted that the belt 81' is narrow 85 enough and so placed with respect to the rear line of the box as to permit the roll 84 to roll up the back of the box. Registering at a position earlier than that at which the rolling-up takes places requires an extra operator but 90 permits more rapid operation.

85 The members 86 and 86' that support the box from moving during the initial rolling are chamfered at 106 and 107 respectively to 95 permit easy entrance of the successive boxes. The member 86 is carried upon suitable brackets 108.

90 Features of the invention shown on Sheet 1 (Figures 1 to 4) include mechanism for facilitating registration of the boxes upon the 100 wraps while they are still on a belt conveyer from the glue machine, a construction protecting the conveyer from becoming gradually opaque at the registry station from glue 105 from the glue machine by the use of a sectional conveyer, automatic mechanism for applying the wraps part way up the backs of the boxes before they are to be transferred by operators to the wrapping machine and the 110 operation of the roll, by which the wraps are applied, from the rocker lever which operates the corner-lap movement at the wrapping machine, preferably using the rocker furthest away from the operator in order to be least in the way of the operator. 115

Wrapping machine

120 The wrapping machine with which our invention is embodied is shown in Figure 5 which is a broken elevation partly in section and with many parts removed from the operator's side of the machine. The conveyer section 81' of Figures 1, 2 and 3, at which the wrap is given a preliminary rolling up the back of the box, is not shown because it would 125 extend across and partially hide the operating mechanism of the wrapping machine. The delivery station 109 of Figures 1 and 2 of the conveyer (not shown in Figure 5), is 130 preferably in front of the vertically recipro-

eating box form 110 of the wrapping machine.

In the wrapping machine a driving pulley 111 mounted upon a shaft 112 is driven continuously in any suitable way and has clutch connection at 113 with a sleeve 114 surrounding the drive shaft and carrying a worm 115 in continuous mesh with the worm gear 116 shown upon the lower end of the cam shaft 117.

All of the wrapping movements of the machine are operated through the medium of cams upon this cam shaft which also controls the feed of wraps to the glue machine as all ready explained, and reciprocates the roll 84 for fastening the wraps part way up the boxes before delivery from the conveyer. The machine shown is of well-known type and is adapted to operate upon paper boxes as well as upon cigar boxes.

A split form 110 is mounted with a lower portion 118 carried upon a plunger 119 and an upper portion 120 carried upon a plunger 121. Both of these plungers are adapted to reciprocate vertically being guided in a suitable stationary guide portion 122 of the frame of the machine. The plunger 119 carrying the lower form is positioned vertically by a cam groove 123 around a drum 124 upon the upper end of the cam shaft, by means of roller 125 upon a rocking lever 126 and link 127 between the lever 126 and the plunger. The lever 126 is pivoted at 128 in a suitable fixed bearing 129.

The plunger 121 carrying the upper form comprises vertical rods 130 which slide through perforations in a flange 131 at the lower end of the plunger 119, are suitably guided in the stationary frame structure and are connected together at the top by a head 132. A tension spring 133 between the head and an anchor 134 upon the lower plunger spring-presses the plungers to bring the upper forms together, so that vertical reciprocation of the plunger carrying the lower form will effect a corresponding vertical reciprocation of the other plunger as long as this other plunger is free to move.

Vertical stripper rods 135 are adjustably mounted upon a lower yoke member 136 which is carried upon the lower ends of vertically slidable rods 137 guided at 138 and 139 to vertical movement only. The stripper rods have universal adjustment and are set to operate vertically in and out of suitable vertical perforations 140 in the upper and lower portions of the split form.

The rods 137 are connected at the top by an upper yoke 141 and vertically positioned by a cam 142 around the drum 124 in cooperation with roller 143, rocker lever 144 and link 145 between the lower yoke 136 and the rocker lever 144.

The head 132 connecting the rods 130 that support the upper form 120 carries a down-

wardly extending and vertically adjustable stop rod 146.

The lower end of this rod 146 engages the top of lever 144 at one portion of the downward movement of the plunger 119 carrying the lower form, thereby causing separation of the upper and lower forms against the action of the spring 133. The upper form thus moves in response to any movement of the lever 144 and therefore with the strippers 135 when the stop rod 146 and lever 144 are in engagement and at other times moves in response to the vertical movements of the lower form.

The box 147 having a wrap 71 fastened to its bottom and turned part way up the back of the box to prevent its catching upon the block 148 of the wrapping machine is applied to the form while the two portions are together, an operator pushing the box upwardly so that the form fits the inside of the box. After this has been done an operator starts the downward movement of the form at a treadle 149 which permits clutch engagement at 113 starting rotation of the cam shaft 117 and the cycle of wrapping operations.

The block 148 being a well known standard part of the wrapping machine is shown in fragment only. When the form is in its upper and receiving position the block is sufficiently beneath the form to be out of the way when putting a box on the form. The block is resiliently pressed upwardly toward its upper position by a spring 150 and presents an upper face registering with the bottom of the box during the successive wrapping operations, tightly pressing the wrap to the bottom of the box throughout these operations, moving down as the form moves down and subsequently rising as the form rises until the block again reaches its upper position where it comes against a suitable stop and ceases to follow the form upwardly the form continuing upwardly after the wrapping cycle has been completed to its receiving position.

In its downward travel with box and wrap in place the form brings the bottom of the box sharply against the block 148 pushing the block downwardly ahead of it against the action of the spring 150, and carries the box between the front and rear brushes 151 and then between the front and rear rolls 152, which sweep and roll the front and rear projections of the wrap up the front and rear sides of the box. The form and box then come to rest, both portions of the box form being inside the box and filling the box.

When the box has come to rest the corner-lap mechanism moves in from front and rear respectively lapping over the projecting ends 125 of the turned up sides across the ends of the box, after which the form and box again travel downward between end brushes 153 and between end rollers 154 which sweep and roll up the end portions of the wrap over the ends 130

of the box (only one end brush and one end roll being shown in the illustration to come to rest again somewhat below the end rolls for the turn-in operation.

5 Before the box form comes thus to rest preparatory to the turn-in operation the upper portion of the form has separated from the lower portion by reason of engagement between the stop rod 146 and the top of the lever 144 so that when the boxes have come to rest the second time preparatory to turn-in the upper form is out of the way above the box.

10 Turn-in members now move inwardly and again outwardly over the respective sides and 15 ends to turn the upwardly projecting ends of the wraps in over the top of the box, the reciprocation of the turn-ins being effected by a rocker lever 155, linked at 156 to a sleeve member 157 having four radially extended arms 20 158, one upon each side of the box, each arm carrying a vertical rod 159 connected by a suitable link 160 to a bell crank 161 for reciprocating the turn-in mechanism (Figures 5, 18, 19, 24 and 25).

25 After the turn-in operation has been completed the upper form moves down into the box to turn the inwardly projecting ends of the wrap down into the box.

30 The box form carrying the wrapped box then moves up, the upper and lower forms being together and inside the box, until at one point of the up-stroke the bottom of the box is engaged by the downwardly directed lower ends of the stripper rods. These rods 35 are usually stationary during stripping, the forms moving up as a unit while the box is held back and pushed off by the stationary rods on to the felt covered block which has followed the forms up to its initial position and then stopped while the forms are still 40 traveling upwardly. Normally the box is stripped from the forms after the felt block has again reached its initial position with the bottom of the box at this position during 45 the stripping process. After the stripping is complete the strippers move up out of the way and a spring ejector flies over and knocks the box away from the machine.

50 The procedure at the wrapping machine of Figure 5 is old, as thus far described, as applied to paper boxes. The wrapping machine portion of our invention is intended particularly to apply to cigar box wrapping and is directed to mechanism mounted upon 55 the corner-lap plate holders to effect turn-in and slitting of the droplid ends simultaneously with the corner-lapping. It is also directed to a novel form of turn-in members, to mechanism upon the upper form for effecting the turn-down of the wrap into the box after the operation of the turn-ins, and also to cooperating mechanism upon the upper form and upon the presser block holders for effective turn-down at the droplid 60 ends of the box above the edges of the front 65

and rear sides. In the prior art presser members upon each side of the box move in against the box when the upper form has moved down into the box to turn the inwardly projecting ends of the wrap down into the box, 70 their function being to press the sides inwardly upon the turned down wrap portions while the latter are held out by the upper form.

We normally dispense with these pressers 75 of the prior art, finding them usually unnecessary when wrapping cigar boxes, but find some moving portions of the old pressers afford convenient mountings for novel constructions cooperating with new expanding mechanism of the upper form, as mentioned above and described later.

Lower form: (Figures 5, 14, 17, 18, 23, 24 and 25)

85

The lower form 118 fits the inside of the box and against the bottom of the box and remains in place against the bottom of the box from the time that the box and wrap have been put on the form by an operator 90 until the box is removed by the strippers. It is carried upon a spur 163 which is received in a suitable recess in the plunger 119 being held to place in any suitable way as by a set screw 164. This spur is usually of 95 circular section. The spur is provided with a flange or plate 165 at its lower end by which it is fastened securely to the lower form, the form being usually wood. The form is perforated at 140 to pass the stripper rods and 100 is suitably recessed at 166 to provide clearance for parts of the upper form.

The upper corners and edges of the form are chamfered off at 167 to effect a more easy disengagement from the turned down 105 portions of the wrap during stripping and to lessen any danger of the turned down portions of the wrap being displaced from the inside of the box during stripping tearing loose.

Upper form

Modifications of the upper form are shown respectively in Figures 6 to 9 and Figures 10 to 13. It is perforated at 168 to pass 115 the supporting spur 163 of the lower form and comprises a metal plate 169, roller mechanism 170 and expansion mechanism 171.

The plate 169 is fastened by screws 172 to the lower end plate 173 of the plunger 120 121 and overlaps the tops of the long sides of the box between the droplid ends. Longitudinally it is suitably somewhat shorter than the distance between the droplid ends 174 of the box and carries the end expansion 125 members 175 on its upper side that preferably hook over the ends of the plate at 176 and are spaced so that their outer edges before expansion lie somewhat back of the droplid ends of the boxes.

130

The ends of the plate 169 and the hook portions 176 of the expansion members are normally sufficiently back from the droplid ends to be out of the way of slitting knives 225 (described later) that we mount upon the corner-lap plate holders. These knives move in between the droplid ends and the members 176 to upwardly slit the up-turned long side flaps at the droplid ends preparatory to corner lapping and turning-in the long side flaps at the droplid ends.

The four roller members, one for each side, are carried upon the lower side of the plate and are spring-pressed outward toward positions beyond the inside lines of the box, being forced back somewhat against the action of their respective springs whenever a box is put to place over the form. They assist in supporting the inside of the box during the turning up of the sides and ends of the wrap and subsequently serve to roll down the turn-in portions of the wrap into the box.

The rollers conveniently comprise sections of rubber tubing 177 over metal rods 178 that turn in suitably spaced bearings 179 spring-pressed outwardly to the desired positions.

In the construction shown in Figures 6 to 9 these bearings comprise inclined rocker members 180 pivotally supported at 181 upon metal corner members 182 fastened to the lower side of the plate 169. Each corner member gives bearing support for two of the rocker members and is perforated at 150 to pass the strippers.

There are thus two rocker members upon each side of the form, supporting the roll of that side, and extending diagonally upward from the pivots 181 to the roll and shown with diagonally inwardly extending arms 183 to tension springs 184 that are stretched between the inner ends of the arms and suitable cross bar anchors 185 above the plate, which is shown with perforations 186 to pass the springs.

The outward movement of the rockers is limited by suitable stops which may comprise suitable lugs upon the corner members 182 in position to engage the inwardly extending arms of the rocker members when the rolls are in their desired outer positions.

Mounting the bearings of the rolls upon rocker members that extend diagonally downward beneath the plate 169 gives an upper form that is relatively thick in a downward direction beneath the plate 169.

This is not at all disadvantageous when the form is used with full depth cigar boxes. When wrapping half depth boxes however it is desirable to have a shallower form and in this event we may extend the rocker members diagonally upward to pivot supports above the plate or as illustrated in Figures 10 to 13 mount the bearings upon horizontal plunger rods 188 operating in a suitably shallow guiding member 189 and spring-pressed

outward at 190 to suitable screw stops 191. Most of the expansion mechanism above the plate 169 is not shown in Figures 10 to 13 which are intended to illustrate merely the plunger type of support for the rolls beneath the plate.

Normally the rocker type of roll support is preferable to the plunger type in that the rockers wear better than the plungers.

The distance between the outside surfaces of rolls upon opposite sides of the box is normally greater than the corresponding inside dimension of the box so that when the form is inserted in a box the rolls are deflected inwardly against the action of the respective springs.

The rolls at the back of the box are desirably provided with end sections 192 that extend outwardly to fit against the ends of the box. This is particularly desirable when a form of wrap is used that is cut away at an intermediate portion 193, Figure 36. This recessed wrap leaves an uncovered space on the back of the box for a hinge member and leaves relatively short turn-in sections 194 adjacent the ends.

In view of the shortness of these wrap sections to be turned down inside the box at the back it becomes increasingly important that the turning down operation should be such as to insure close contact between these portions and the inside surface of the box; otherwise they are likely to come loose. The turn-down portion 195 of the wrap at the front of the box is normally the full length of the box and it is of relatively lesser importance to obtain perfect contact between the inside front of the box and the wrap adjacent the respective front corners than at the short sections 194 at the back corners. As it is desirable to roll to place the turned down portions 196 of the wrap on the ends of the box we prefer to make the end rolls extend forwardly at 197 to the front line of the box and for this reason the end sections 198 of the roll for the front of the box are shown shorter than the corresponding sections 192 of the back roll and end sufficiently inward from the end lines of the box to pass the end rolls at 197.

The expanding mechanism 171 above the plate 169 functions with cooperating external mechanism to press the turned down wrap into the droplid corners of the box. These corners are inside the droplid ends 174 and above the front and rear sides of the box and the expanding mechanism about to be described has greatly improved the finish and commercial appearance of the wrapped box.

Expansion members 175 adapted to relative expansion and contraction are mounted on the opposite ends of the plate 169. They are spring-retracted at 199 toward relative contraction, are turned down at 176 over the edge of the plate 169 to provide

bearing engagement to the bottom of the droplid corners and are adapted to be relatively expanded by the operation of bell crank rockers 200.

5 The levers 200 are pivoted at 201 to the plate and have one arm pivotally connected at 202 to a cross similar link 203 that is connected at its ends by links 204 and 205 to spaced portions of the expansion member.

10 The other arm of the lever is provided with a forwardly projecting lug 206 near the middle of the front of the box. These levers are counterparts as best seen in Figure 6. The extension is effected by engagement between a presser member 207 Figures 19, 23 and 25 and the lugs 206, the force of expansion being supported upon the outside of the box by felt covered blocks 208 operated by the same mechanism which operates the turn-ins, see Figures 5, 18 and 19.

15 The expansion members are suitably limited to rectilinear movements, each member being shown slotted toward opposite ends at 209 to pass guiding posts 210 mounted in 20 the plate.

25 The mechanism for pushing the lugs 206 and for supporting the expansion force against the inside of the droplid ends at the opposite sides of the box is described later in 30 greater detail. The rolls and expansion mechanism of the upper form are all new and very useful in making the wrapping more effective and of better appearance.

35 The rolls and expansion mechanism are shown in Figures 5, 15, 16 and 22. They are associated with corner-lap mechanism of the prior art, and comprises additions to the former corner-lap units. There are four of 40 these units 211 one at each corner of the box for corner lapping and for slitting and turning in the long sides at the droplid end. The units are adjustably mounted upon the corner-lap plate holder bars 212 of the prior art which operate respectively in front and 45 back of the box, Figure 5.

50 The bars 212 are rigidly fastened to blocks 213 each of which ties together the inner ends of longitudinally slidably outwardly extending horizontal rods 214 and 215. These 55 rods are connected to a common yoke near their outer ends, which in turn has suitable link connection 94 to rocker members 93 (Figures 4 and 5), which are in turn linked to the T rocker 102 operated by the cam 104. This mechanism for moving the mounts of the units 211 need not be shown in detail, being well-known mechanism of the type of machine illustrated.

60 These units 211 are adjustable to different positions along the bars 212 in order to accommodate the units to boxes of different sizes.

65 In the prior art the corner-lap plates 216 are removably fastened at 217 to a hinge member 218 that is pivotally mounted upon

a pintle post 220 on a bracket member 221 and is spring-pressed at 222 to a suitable stop upon the bracket to maintain the desired alinement for resilient corner-lapping. The bracket member 221 carries the unit and is preferably adjustable along the bar 212.

70 We make the pintle post 220 rigid with the bracket 221, extend it above the hinge member, and rigidly fasten an arm 223 upon the extended portion 224 of the post and in alinement with the box ends.

75 Upon the inside of the arm we mount a slitting knife 225 having an upwardly directed cutting edge 226 alined to slit the upturned portions of the long sides adjacent the droplid ends when the units move inward preparatory to corner lapping. The point 227 of the knife is alined with the box corner between the droplid end and long side. On top of the arm we fasten a presser spring 80 228 shown held to place by a screw 229. This spring is alined with a box end and curves around the forward end of the arm 223 extending back under the arm at 230. They serve as turn-in members for the portions 85 of the turned up long sides that are at the droplid ends.

85 The knife preferably extends sufficiently ahead of the forward edge 231 of the corner-lap plate and beyond the spring 228 to effect 90 the slitting before corner lapping and spring turn-in operators.

95 The corner-lap plate preferably upwardly overlaps the lower portion of the spring and the arm 223, which may, if desired, serve 100 as the stop to limit the closing movement of the lap plate and to determine its initial alinement.

105 The units 211 at opposite ends of the bars 212 are opposite counterparts and, therefore, are not interchangeable upon the same bar although the units on one bar are interchangeable with the units on the other provided that the right-hand unit of one bar is made the left-hand unit of the other and vice versa.

110 The slitting operation takes place preferably before the corner-lapping, the points of the two knives striking the turned up long side laps at the inside corners of the 115 droplid ends.

115 As soon as the slitting is complete, or optionally somewhat before this time, the corner-lap plates lap over the projecting ends of the wrap and the presser springs turn in 120 the upwardly projecting portions of the wraps at the droplid ends down on to the droplid ends.

125 The turn-in of the short sections above the droplid ends and the corner-lapping at the ends is preferably simultaneous, the corner-lap plates desirably closing against the outer sides of the presser springs as well as engaging the faces of the box. As a result there is a sharp crease 232 made be- 130

tween the corner-lap ends and the turn-in section above the droplid ends. This crease is best seen in Figure 32 which shows a fragment of box and partially folded wrap after the slitting, corner-lap and droplid end turn-in mechanism has moved in, the mechanism itself not being shown in this figure.

Structurally the new features added to 10 the corner-lap mechanism of the prior art include the slitting knife, droplid end turn-in spring and supporting arm all rigidly fastened to the bracket member 221, preferably fastened upon the extended end of the 15 pintle 220 which is then rigidly fastened to the bracket.

The units move in to the corners of the box from front and rear while the box is temporarily at rest, slitting, turning in over 20 the droplid ends and corner lapping on the way in. The lower form then carries the box down while the units 211 are still at their inward position, the lap plates 216 wiping up the laps of the wrap as the box 25 moves down between the end brushes 153 and between the end rolls 154 to turn up the ends of the wrap.

The box and lower form now come to rest for the operation of the turn-ins, the 30 upper form having been left out of the way somewhat above the box, and the wrap sides and ends, except for the small portions of the long sides over the droplid ends, projecting above the top of the box.

55 Turn-ins.

With the box at rest and the upper form out of the way above the box, the side turn-ins move in and out at the sides and the 40 end turn-ins in and out at the ends to turn-in the upwardly projecting portions of the wrap over the sides and ends of the box.

In the prior art these turn-ins have been 45 rigid plates mounted to move together in and out across the tops of the sides but appreciably above the box edges so as to carry the paper in as distinguished from pressing the paper down against the flat edges.

We have found it advantageous to mount 50 the turn-in plates upon spring hinges to be deflected upwardly slightly during the turn-in operation and also find it more desirable to roll the paper in as at the ends, as compared with the wiping movement of the 55 plate used for the long sides because of the limited height available there.

Our long side turn-ins are best seen in 60 Figures 20, 23, 25 and 26. We hinge the turn-in plate upon a plate holder 234 using 65 spring hinges 235 that normally press the turn-in plate to its seat 236 on the holder.

The holder fits upon a block 237 guided to rectilinear movement by horizontal supporting rods 238 and operated (Figure 5) 65 from the cam groove 239, roller 240, rocker

155, central sleeve 157, vertical arm 159, link 160, rocker 161 and link 241. It is desirably fastened to the block by a single screw 242.

The holder 234 is an integral member interlocking with its supporting block 237 and 70 vertically recessed at each end at 236 to form flat seats for outwardly projecting portions 243 of the turn-in plate. The plate clears the intermediate portion 244 of the holder and is of length to fit between 75 the droplid ends of the box.

We mount spring plungers 245 at the ends of the plate. These plungers present faces 246 against the ends of the droplid ends during the turn-in operation of the 80 plate 233, firmly holding the turned up portions of the wrap to place against these ends until the turn-in operation is over, which prevents loosening of the wrap at these ends as the turn-in is withdrawn and insures perfect gluing contact at these small end surfaces.

Guide rods 247 of the plungers operate in casings 248 that may be integral with holder 234 or fastened to it as at 249. The 90 plungers are spring-pressed forwardly at 250 to present the forward faces 246 of the plungers to the forward edge 251 of the turn-in plate except when pressed back during the turn-in.

The novel features upon the long side turn-ins include spring hinging the turn-in plate to its holder so that the plate is deflected upwardly against spring action during the turn-in operation, and mounting spring 100 plungers at the ends of the plate to hold the wrap firmly to place over the droplid ends during the turn-in operation.

The end turn-ins are best seen in Figures 27, 28, 18 and 19, and each comprises a roll 105 252 having end journals 253 supported in bearing members 254 that are pivoted at 255 to the opposite ends of a turn-in holder 256. The bearings are individually pressed to pin seats 257 of the holder by flat springs 258 110 fastened to the holder, the roll 252 being deflected upwardly slightly during the turn-in, against the springs 258.

The advantage of having the bearings thus 115 relatively movable vertically lies in that they exactly accommodate the roll to the top of the box irrespective of any small variations of initial alinement between the tops of the boxes and the roll.

The spring plungers 245 at the ends of the 120 side turn-ins cooperate with the end turn-ins to hold the small portion of paper previously cut so that it will not be disturbed by the end turn-ins in order thus to secure exact folding on top of the droplid ends—and to a lesser 125 extent cooperate with the side turn-ins for perfect wrapping adjacent the slits at the droplid ends.

The end turn-in holder fits upon a block 259 generally similar to the blocks 237 of the 130

long side turn-ins, carries horizontal supporting and guiding rods 260 and is operated from the central sleeve 157, vertical arm 159, link 160, rocker 261 and a link 262 to the block 259 (Figures 5, 18 and 19) similar to the rocker 161 and link 241 of the long side turn-ins.

Novel features in the end turn-ins include the use of a roll to effect turn-in, spring hinging the turn-in member to its holder, and making the opposite ends of the end turn-in members relatively vertically movable for accommodation to variant box alignments.

After the turn-in operations have been completed the turn-in members move back out of the way and the upper form now in position above the box descends into the box to effect turning down the inwardly projecting ends of the wrap on to the inside surface of the box.

The rolls (Figures 7 to 9) mounted along the sides of the forms upon the bottom of the plate 169 normally project slightly beyond the inside lines of the box and are forced inwardly as the rolls enter the box resiliently pressing the inwardly projecting ends of the wrap against the inside surfaces of the box.

The expansion members 175 upon the top of the plate 169, shown in Figures 6, 8 and 9, are provided with slightly projecting end portions 176 as already described, adapted to be pushed outwardly into the droplid corners above the long sides by pressing the lugs 206 presented by the rocker members 200.

We effect this expansion by engagement between the projecting end 263 of a presser or push member 207, (Figures 19, 23 and 25), and the lugs 206 of the rocker members 200.

As the ends of the expansion members engage the inner surfaces of the droplid ends felt covered supporting blocks 208 (Figures 18, 19, 53 and 55) move in and engage the outside of the box at the respective droplid ends opposite to the engaging ends of the expansion members in order to support the pressure exerted by the expansion members upon the inside.

Both the push member 207 operating the expansion members and the supporting blocks 208 externally supporting the outward expansion pressure as well as all four turn-ins are operated by the vertical reciprocation of the central sleeve 157 through the operation of the rocking lever 155 and cam 239 (Figure 5).

The push member (Figures 23 and 25) is operated by the reciprocation of a vertical rod opposite one of the long sides of the box, this rod being one of the rods 159 rigidly supported by the arms 158 of the central sleeve 157, and operating as already described.

The long side turn-ins (Figures 20, 23 and

5) together by the head 237 carrying the long side turn-in and having a knuckle connection 265 with the link 241 to the bell crank 161 (already described) rocked by the vertical reciprocation of the central sleeve 157 (Figure 70

The push member 207 is mounted upon a vertical arm 266 that is supported between a pair of horizontally spaced and longitudinally slidable rods 267, of which only one is visible in the figures.

The inner ends of these rods rigidly connect with a block 268 that presents on its outer side a cam lug 269 against a cam 270 upon the hub of the rocker member 161.

The rods 260 are spring-pressed at 271 to position away from the box to maintain engagement between the cooperating cam members 269 and 270.

During the turn-in operation the vertical rods 159 move upwardly from an intermediate position and then downwardly to a low position. During the upward movement the long side turn-ins 272 and short side turn-ins 273 move inwardly over the respective sides 90 of the box to effect the turn-in, and during the downward movement of the rod 159 the turn-ins move back out of the way.

At the beginning of this downward movement the upper form 120 then suspended above the box and above the turn-ins, moves down on to the rolls of the end turn-ins, and moves quickly into the box under the action of gravity and of the spring 133 when these rolls move out from under, the inwardly projecting ends of the wrap being rolled downwardly against the inside surface of the box during this entry of the upper form into the box.

The end rolls resiliently press the end turn-in flaps down upon the tops of the droplid ends while rolling inwardly. They roll inwardly somewhat beyond the inner edges of the droplid ends and springing downwardly when they pass the inner edges crease 110 the wrap along the respective inner edges. This creasing is preferably greatly accentuated by the descent of the upper form, the end rolls on the bottom of the upper form at this time coming down and stopping against the turn-in rolls which are then pressed downward by the weight of the upper form as well as by their own downwardly pressed springs.

The downward movement of the rod 159 continues beyond that requisite to move the turn-ins back to their initial position and during this continued downward movement engagements between the cooperating cam surfaces 269 and 270 forces the block 268 inwardly toward the box, thereby moving the

droplid corners of the box as already described.

Simultaneously with the inward motion of the push member 207 the supporting blocks 208 have been moved into position against the ends of the box opposite the droplid corners, to support the outward pressure of the expansion members.

These supporting blocks 208 (Figures 18, 19 and 53) are moved by the rockers 261 of the end turn-ins in the same general way as the corresponding rockers 161 of the side turn-ins move the push block.

Referring to Figures 18 and 19, the supporting members 208 are preferably pieces of felt at the opposite ends of a block 274 that is rigidly fastened at 275 to a longitudinal slidable member 276 similar to the member 268 (Figures 23 and 25).

The member 276 is rigidly fastened to the inner ends of horizontal spaced rods 277 spring-pressed away from the box at 278 and positioned by cooperating cam surfaces 279 and 280 respectively on the member 261 and the rocker 276.

Novel features of the mechanism positioned by the rocker members 161 (Figures 18, 19, 23 and 25) include the push member 207 for operating the expansion members on the upper form and the supporting blocks 208 for externally supporting the outward pressure of the expansion members.

Cycle of operation

Figure 37 indicates diagrammatically a desirable cycle of operations when the invention is embodied upon a wrapping machine of the type shown. Some of the operations indicated upon the cycle may be very considerably modified if a different type of wrapping machine is used, and some of the movements indicated are unnecessary during the wrapping operation of the invention, the movements being taken from a well-known machine of the prior art and are in some instances to adapt the machine of the prior art to operations foreign to the present invention.

Vertical ordinates on this chart represent the simultaneous positions of the respective parts throughout a single cycle, the common abscissa representing time and the respective parts being shown by suitable notations on the different curve lines which are also lettered for greater convenience of reference. The different movements are away from and back to initial positions, some of them being down and up and others horizontally inward toward the box and again backward from the box.

Preparatory to the cycle an operator places a box from the conveyor over the form of the wrapping machine. This box has a wrap glued to its bottom rolled a little way up

back and the operator pushes the box so that the forms enter the box until the side edges of the box between the droplid ends engage the overlapping sides of the plate 169 of the upper form.

The clutch is then released at 281. The forms carrying the box and both inside the box, travel downward, the bottom of the box striking the felt covered block 148 at 282 while the box is still well above the long side brushes 151.

The block, box and forms continue downward together to a point 283, where they come to rest after having passed between the long side brushes 151 and the long side rolls 152 which turn up the long sides of the wrap.

The region from 281 to 282 on the chart is that during which the box and forms are travelling downwardly across the vertical clearance space necessary to allow the operator to satisfactorily place the box upon the form.

Between the points 282 and 283 after the engagement between the bottom of the box and the felt covered block, the side wrapping is effected, the box and forms coming to rest at 283.

Between the points 283 and 284 the box is at rest and during this period from the point 285 to the point 286 the rocker member 93 (Figures 3 and 5) operates slitting of the turned up wrap at the droplid ends, corner lapping and turning in the sides over the droplid ends and also moves the roller 84 (Figures 1 to 3) to roll a new wrap part way up a new box, on the belt conveyer 81'.

With the corner-lap plates and associated mechanism stationary at the end of their inward travel, and the roll 84 also stationary, in its raised position where it is pressing the new wrap to place against the back of a new box, the box and forms again travel downward between the lines 284 and 287 and wrapping taking place between the points 284 and 287 while the box, with both forms inside, descends between the opposing end brushes and opposing rolls, the end portions of the wrap being swept and rolled up the ends of the box to project above the box.

After the end wrapping has been completed the upper form stops in its descent due to engagement between the rod 146 carried by the head 132 of the rods 130 carrying the upper form with the top of the auxiliary lever 144.

Between the points 287 and 288 the upper form is stationary while the box and the lower form inside the box keep on descending while the corner-lap plates and associated mechanism are moving back out of the way with the result that at point 288 at which the box and lower form come again to rest the upper form is suspended stationary above the box where it is out of the way. The corner-

lap plates and associated members move back out of the way between points 289 and 290.

With the box stationary and the upper form suspended above the box the turn-in plates and rolls between the points 291 and 292 move in from the sides and ends to turn-in the upwardly projecting portions of the ends and sides of the wrap over the top of the box.

Between the points 293 and 294 the stripper rods are moving down permitting the upper form to move down under the action of the spring 133 Figure 5 and of its own weight until at a point 295 the end rolls of the upper form engage the end turn-in rolls then above 15 the ends of the box which temporarily stops further descent of the upper form.

At the point 296 the turn-in rolls and turn-in plates begin to move back and a moment later at the point 297 the end turn-in rolls 20 move out from under the end rolls of the upper form permitting the upper form to move down quickly at 297 into the box to effect turning down the inwardly projecting portions of the wrap on to the inside surfaces 25 of the box.

The stripper rods continue to move down to a point 294 where they come to rest due to proper figuration of the stripper cam 142 (Figure 5).

Between the points 298 and 299 the box and both forms inside the box are moving down into position for the operation of the expansion mechanism and the cooperating supporting blocks to effect firm application 35 of the wrap at the ends of the droplid ends above the sides of the box.

Between the points 300 and 301 the expansion mechanism and cooperating supporting blocks are moving to position for maximum 40 compression of the turned down wrap into the droplid corners, this maximum compression continuing unabated to the point 302 when a releasing movement begins that is complete at the point 303, the turn-in members moving incidentally further away from 45 the box during the releasing period.

The box, both forms inside the box and the felt covered block 148 beneath the box start to rise at the point 304.

At the point 305 the felt covered block 50 which has been keeping in contact with the bottom of the box during its rise up to this point reaches the limit of its upward travel and becomes stationary, the stripper rods having at point 294 moved down to a point 55 at which their lower ends are substantially at the upper limit of travel of the block 148. As a result the stationary strippers penetrate the forms at about the point 305 and prevent 60 the box, which is now completely wrapped, from rising beyond the upper position of the block 148.

The continued upward movement of the forms while the strippers are stationary results in stripping the box from the form 65

which takes place between the points 305 and 306.

At the point 306 the strippers start to rise and are out of the box before the point 307 at which an ejector tube 308 (Figure 5) flies 70 out and knocks the completely wrapped box away from the machine.

At the point 309 the clutch is automatically released and the cycle is complete.

Though we have used a cigar box wrapping machine and the application to a cigar box as examples in that they well illustrate the principles of our invention, it will be noted that the various features of our invention are suited to other boxes than cigar boxes and some of them apply generally in the box-wrapping art.

It will also be evident that part of our invention is applicable quite as well to wrapping the lids as to wrapping the boxes. For this reason the language "box parts" has been used in some of the claims to cover the lids also.

In view of our invention and disclosure variations and modifications to meet individual whim or particular need will doubtless become evident to others skilled in the art, to obtain all or part of the benefits of our invention without copying the structure shown, and we, therefore, claim all such in so far as they fall within the reasonable spirit and scope of our invention.

Having thus described our invention, what we claim as new and desire to secure by Letters Patent is:—

1. In mechanism for wrapping box parts, a plate permitting light to pass through it, a belt engaging the upper surface of the plate and adapted to carry and deliver wraps, a source of light illuminating beneath the plate, and mechanism giving the belt step by step movement and thereby adapting it to deliver successive wraps one at a time to a position of rest above the plate.

2. In mechanism for wrapping box parts a wrapping machine, a belt conveyer adapted to deliver glued wraps to the machine, a plate beneath the belt permitting light to pass through it and engaging and raising the belt to bring the belt into firm contact with the plate, a source of light illuminating beneath the plate, and mechanism adapted to bring successive wraps on the belt successively to rest above the plate by suitable intermittent motion of the belt.

3. In a feeding device for a box machine for wrapping box parts, a belt adapted to receive successive wraps from a gluing machine, a second belt fed with wraps by the first belt and isolated therefrom, and a source of light illuminating beneath the second belt to facilitate registering successive box parts upon the successive wraps while they are on the second belt.

4. In a feeding and registering system for

- wraps intended for a box wrapping machine for wrapping box parts, a belt adapted to be fed with successive wraps from a gluing machine, a second belt fed with wraps by the first belt, a light-transmitting plate supporting one portion of the second belt and a source of light illuminating beneath the plate to facilitate registering the successive box parts with the successive wraps. 5
- 10 5. In mechanism for feeding wraps and box parts to a wrapping machine for box parts, a belt conveyer adapted to be fed with wraps by a wrap gluing machine, a plate permitting light to pass through it and engaging an intermediate portion of the bottom of the belt and adjustable longitudinally of the belt, and a source of light illuminating beneath the plate for use in registering successive boxes with successive wraps. 15
- 15 6. In mechanism for wrapping cigar boxes or the like, a wrapping machine, a belt conveyer for feeding wraps and boxes thereto, and mechanism for rolling one side of the successive wraps part way up one side of the successive boxes preparatory to the delivery of the wraps and boxes from the conveyer. 20
- 20 7. In a device for feeding wraps to a box wrapping machine, a belt conveyer adapted to be supplied with wraps from a gluing machine, means adapting successive boxes to be registered upon successive wraps while upon the conveyer, a second conveyer fed with boxes and wraps from the first conveyer and vertically movable means for applying the respective wraps part way up one side of the respective boxes while said wraps and boxes are located upon the second conveyer. 25
- 25 8. In a box and wrap conveyer to a wrapping machine, a feed belt adapted to feed wraps to a position for box registry, a second belt having one edge alined inwardly from one edge of the registered boxes, means adapted to engage the wraps at portions projecting beyond said belt edge for applying the wraps part way up the respective boxes, and devices for maintaining the boxes in position during said application. 30
- 30 9. In a feeding device for a box wrapping machine, a feed belt adapted to deliver boxes and wraps in relative registry to the machine with one side of the box and wrap accessible from below at one edge of the belt, and wrap applying means adapted to apply the projecting portion of the wrap part way up the back of the box from the bottom. 35
- 35 10. In a machine for wrapping boxes having droplid ends, a corner-lap plate holder, a corner-lap plate pivoted thereon and spring-pressed to its duty and a knife rigidly connected to the holder and adapted to slit the successive wraps upwardly from the droplid end corners of the boxes. 40
- 40 11. In the machine for wrapping boxes having droplid ends, a corner-lap plate holder, a corner-lap plate pivoted thereon and
5. In mechanism for wrapping boxes having droplid ends, a corner-lap plate holder, a corner-lap plate pivoted thereon and spring-pressed to its duty, a knife rigidly connected with the holder and adapted to upwardly slit the wraps adjacent the interior of the droplid end of the box and a spring presser-foot movable with the knife and adapted to turn in and press down the wrap above the droplid end. 70
12. In a machine for wrapping boxes having droplid ends, a corner-lap plate holder, a corner-lap plate pivoted thereon and spring-pressed to its duty, and a presser-foot carried by the holder for turning in and pressing down the wrap upon the top of the drop-lid end. 75
13. In a machine for wrapping boxes having droplid ends, a corner-lap plate, a presser-foot moving with the holder and adapted to downwardly press upon the top of the droplid ends during the corner-lapping and simultaneously to pinch the folded corner-lap against the corner-lap plate above the droplid end during corner-lapping, in order to form a sharp crease between the lap and the turn-in above the droplid end. 80
14. In a machine for wrapping boxes having droplid ends, a corner-lap plate holder, an upwardly cutting knife rigid therewith adapted to operate in line with the insides of the droplid ends of the boxes, and a corner-lap plate pivotally mounted on the holder. 85
15. In the art of covering boxes having droplid ends by wraps and in which the wrap has been spread up the fronts and backs of the boxes, the novelty which consists in upwardly slitting the fronts and backs of the wraps along the inside edges of the droplid ends and in subsequently thereto simultaneously corner-lapping and turning in and pressing down the fronts and backs of the wraps at the droplid ends. 90
16. In a box wrapping machine, a reciprocating turn-in, and spring plungers engaging the wrap at the ends of the turn-in before and during the turn-in. 95
17. In an end turn-in of a machine for wrapping boxes, a mount, a roll thereon spring-pressed to position, and means for reciprocating the mount to pass the roll across the top edge of an end of a box to resiliently bear against the edge and to effect turn-in. 100
18. In the operation of a machine for wrapping boxes having thick walls, the method step which consists in turning in the flaps over the top edges of the box by progressive rolling pressure against the top edges. 105
19. In the operation of a machine for wrapping boxes having droplid ends, the method which consists in turning in the flaps of the droplid ends by progressive rolling pressure, and in continuing the rolling operation beyond the inner top edges of the droplid ends to crease the wrap over the edge for the downward inside turn of the flap. 115
20. In a machine for wrapping boxes having

droplid ends, an end turn-in resiliently pressed downwardly operating means therefor and spring plunger members adapted to maintain engagement with the ends of the droplid ends of each box during the operation of the turn-in.

21. In a machine for wrapping boxes having droplid ends a side support, a turn-in plate thereon and presser members on the support, one at each end of the plate, pressed yieldingly toward the boxes and adapted to press the wraps against the ends of the droplid ends during the turn-in operation.

22. In a machine for wrapping boxes having droplid ends, long side turn-in members adapted to reciprocate across the long sides of a box between the droplid ends to effect the long side turn-ins by progressively moving from outer to inner edges of the box sides while pressing down upon the flaps being turned in and end turn-ins resiliently pressed downwardly and adapted to roll across the droplid ends.

23. In a machine for wrapping boxes, having front and rear rocking levers operating corner-lap mechanism, a conveyer for feeding wraps and boxes to the machine in relative registry with the boxes extending rearwardly over the edge of the conveyer, and wrap-applying means applying a portion of the wrap part way up the back of the box and connections between this means and the said rear rocker.

24. In a machine for wrapping boxes, a box form having upper and lower members and rollers mounted upon opposite ends of the bottom of the upper member for applying the inner portions of the turn-in flaps to the inside of the box by resilient rolling pressure.

25. In a machine for wrapping boxes, a box form comprising upper flap-applying and lower holding members and rollers at opposite ends of the lower side of the upper member for applying the inner portions of the turn-in flaps to the inside of the boxes, said rollers being resiliently pressed apart and having a larger normal relative expansion than the corresponding inside dimensions of the box.

26. In a machine for wrapping boxes, a box form comprising upper flap applying and lower holding members adapted to separate, and rollers mounted upon the four sides of the bottom of the upper member and adapted to roll down the inner portions of the turn-in flaps upon the inside surfaces of the boxes.

27. In a machine for wrapping boxes, a box form comprising upper flap-applying and lower holding members adapted to separate and rollers mounted upon the bottom of the upper member and adapted to roll down the inner portions of the turn-in flaps upon the inside surfaces of the boxes, the

rolls for the back extending substantially to the ends of the box.

28. In a machine for wrapping boxes having droplid ends, a split form comprising upper and lower members, an expansion device mounted upon the top of the upper member adapted to press the turned down portions of the turn-in flaps into the droplid corners of the box and cooperating external mechanism for operating said devices and for supporting the box externally at the respective droplid corners during the expansion.

29. In a machine for wrapping boxes having droplid ends, a split form comprising upper and lower members, rollers for turning down the overlapping portions of the long side turn-ins, mounted upon the bottom of the upper form at front and back respectively, and resiliently pressed outwardly, the opposite ends of the back rollers extending substantially to the inside surfaces of the droplid ends of the box.

30. In a machine for wrapping boxes having droplid ends, a split form having upper and lower members, rollers for turning down the overlapping portions of the long side turn-ins mounted upon the bottom of the upper form at front and back respectively and resiliently pressed outwardly, the opposite ends of the back rollers adapted substantially to fit against the inside surfaces of the droplid ends of the boxes, and rollers for turning down the inwardly overlapping portions of the end turn-in flaps mounted upon opposite ends of the bottom of the upper member, the end turndown rollers being resiliently pressed outwardly and during operation fitting between the front of the box and the rear turn-down rollers, and the front turn-down rollers during operation fitting between the end turn-down rollers.

31. In a machine for wrapping boxes having thick walls, a roller turn-in, and springs at opposite ends thereof presenting the roller to its duty and permitting the roller to accommodate its position to variations in the boxes to be wrapped.

32. In the operation of delivering a wrap for a cigar box member to a wrapping machine, the method which consists in progressively moving the wrap step by step, glue side up, in its own plane toward the machine, in illuminating and supporting the under side of the wrap during an interval between successive step movements, in registering the box member upon the glued surface of the wrap during the interval of under illumination and support and in subsequently progressing the wrap and box member to the machine.

33. In the operation of delivering a wrap and a cigar box to which the wrap is to be applied to a wrapping machine, the method which consists in moving the wrap, glue side up, in its own plane to a position of rest, in illuminating and firmly supporting the

under side of the wrap in its said position of rest, in registering the bottom of the box upon the upwardly directed glue surface of the wrap while thus illuminated and supported from below, in progressing the wrap and box member to a second position of rest, in turning up a flap portion of the wrap over a bottom corner of the box part way up the box side while the box is in said second position of rest, and in moving the box and wrap to the machine.

34. In the operation of delivering a wrap and cigar box member to a wrapping machine, the method which consists in progressively moving the wrap, glue side up, in its own plane toward the machine to a position of rest, in registering the box member upon the upwardly directed glued surface of the wrap while the wrap is in its said position of rest, in progressing the wrap and box in the plane of the wrap toward the machine to another position of rest, in rolling a flap portion of the wrap upwardly over a bottom edge of the box and part way up and against the side of the box and in progressing the box and wrap to the machine.

35. In the operation of a wrapping machine when wrapping a box having drop lid ends the method of turning in the wrap flaps of the drop lid ends which consists in progressively rolling the flap ends inwardly from the outside top edges of the drop lid ends to points upon the inner edges of the drop lid ends and in creasing the rolled in flaps upon the top inside edges of the drop lid ends by strongly pressing the flaps downwardly upon the inside edges of the drop lid ends after the rolling turn-in operation has been completed.

36. In the operation of a machine for wrapping boxes having drop lid ends, said machine having turn-in rolls and upper and lower forms, the upper form being raised during the turn-in operation, the method which consists in turning in the flaps of the drop lid ends by rolling movements of the rolls inwardly upon the flaps to points upon the inner edges of the drop lid ends and in creasing the inner edges of the turned in flaps over the inner edges of the drop lid ends by moving the upper form down upon the turn-in rolls while they are at said points so that the upper form presses the turn-in rolls down upon the inner edges of the drop lid ends with the turned-in flaps between the edges and the rolls.
